UNITED STATES PATENT OFFICE.

JOHN BYRON GOLDSBOROUGH, OF CROTON-ON-HUDSON, NEW YORK.

METHOD OR PROCESS OF ANCHORING STEEL PILES.

1,164,085.

Specification of Letters Patent. Patented Dec. 14, 1915.

Application filed November 11, 1913. Serial No. 800,248.

To all whom it may concern:

Be it known that I, JOHN BYRON GOLDSBOROUGH, a citizen of the United States, and resident of Croton-on-Hudson, in the county 5 of Westchester and State of New York, have invented a certain new and useful Method or Process of Anchoring Steel Piles, of which the following is a full, clear, and exact description, reference being made to 10 the accompanying drawings, forming part of this specification.

This invention relates to improvements in the art of forming steel pile-foundations on which to erect buildings and other structures, and the invention consists in the method or process which is herein described and claimed of anchoring a tubular pile by attaching it at the base to the bearing-stratum after the pile has been driven 20 through the overlying soil.

On the accompanying sheet of drawings, on which like reference-numerals designate like parts of different views, Figure 1 is a sectional elevation of a pile-cluster with 25 grillage and a column, which forms part of the frame of a building, supported by the pile-cluster, and illustrates the practice of the method when the soil is dry and but one anchor is required to each pile; Fig. 2 is a sectional elevation of an anchored pile, and illustrates the practice of the method when the pile is driven in quicksand and but one anchor is required to a pile; Fig. 3 is a sectional elevation of a large pile an- 30 chored at four places, this view illustrating the practice of the invention in anchoring some piles; and Fig. 4 is a cross-section of this large pile. Figs 5 to 9 illustrate the several successive steps necessary to carry 35 out the invention.

The steel piles to be anchored by the method herein described are heavy steel cylinders which are driven by suitable means, such as a steam hammer or a common pile-driver, to hard rock, and which are filled with plastic material, usually concrete, in which reinforcing devices are or may be embedded and which will harden to form solid columns tightly incased by 45 the steel cylinders. The cylinders vary in diameter, those generally used being twelve-inch cylinders, and they are driven to depths 50

that range from less than twenty feet to upward of sixty feet. If a pile is longer than the standard pipe-length, it is formed of 55 sections, and a "sleeve" or "sleeves" fitting snugly in them, each "sleeve," which is a short steel tube, extending into two sections from their adjacent ends, which abut on each other or else rest against a rib 60 formed on the "sleeve." When the pile is being driven it contains a pointed steel plunger which fits in and extends through it and on which is a fast collar that rests on the top of the pile. The pile-hammer 65 acts on the plunger and this forces the pile down and prevents any earth from entering it, so that after the pile has been driven to the bearing-stratum and the plunger has been withdrawn the interior of the pile is 70 an unobstructed space extending from the top of the pile to the bearing-stratum and ready to be filled with concrete.

The cluster of three piles illustrated in Fig. 1 comprises cylinders 1, 2 and 3 (shown 75 broken) that have been driven through soft soil 4 to the solid rock or bearing-stratum 5. On these piles are caps 6, and grillage-beams 7 extending across and resting on the caps. The steel column 8 of the framework stands 80 on these grillage-beams which together with the tops of the piles and the column 8 are contained in the wall 9 of the building, the wall being represented with a portion broken away to expose them.

It has been the practice in forming a steel pile-foundation to drive the piles as above described and then fill them with concrete, and if the bearing-stratum is level, and the piles are not subjected to unbalanced pressures, it is usually safe to depend on friction between the bearing-stratum and piles, and on the soil surrounding them, to prevent them from slipping sidewise, although sometimes the entire load carried by a pile 95 has been imposed on a solid point or on one edge of the pile. But in neither of these cases are piles so held that they are not liable to slip and let the walls supported by them settle, especially when the surface 100 of the bearing-stratum is sloping. Then a conical point is apt to be more dangerous than the flat end of a pile.

It is the object of this invention to enable

steel piles to be anchored, or attached to the bearing strata to which they are driven, so that they will not be liable to slip sidewise, even if the surfaces of those strata are not smooth or level.

In Fig. 1 three slightly different ways of practising the invention are illustrated. To anchor a pile so that it will be attached to the bearing-stratum as is the pile which includes the cylinder 1 (Fig. 1): a hole 10 is cut in the bearing-stratum, the cutting-tool being applied thereto from within the cylinder or tubular pile, the hole and interior of the pile are cleared, the material being blown out by compressed air or otherwise removed from them, and the hole and pile are filled with concrete or similar plastic material that will harden, combined if desired with reinforcing devices embedded in it. After the filling, or the plastic material included therein, has become hard the pile will be firmly anchored to the rock by the portion 11 of the solid pile, extending to the bottom of the hole 10, so that the lower end of the pile will be kept in its proper place if it should tend to slip in any direction.

The means shown by which the piles that include the cylinders 2 and 3 are anchored comprises a post 12 extending from the cylinder 2 into the bearing-stratum, and the rod 13 extending through the cylinder 3 and thence into the bearing-stratum, the post and rod being preferably steel. The post may be tubular and for the rod a tube may be substituted. The hole required in the bearing-stratum for the post is cut with a drill or similar tool, applied to the bearing-stratum from within the tubular pile, the hole and interior of the pile are cleared, the post is inserted in the hole, and the interior of the tubular pile is filled; and in like manner a hole is cut in the bearing-stratum with a drill or other tool applied to it from within the cylinder 3, the hole and interior of the pile are cleared, the rod is inserted in the hole, and the tubular pile is filled. The filling of each of these piles is, or may be, like that of the pile which includes the cylinder 1. The rod may be secured at its upper end to the superimposed structure, and either the rod or post, or both, may be fastened to the rock with grouting, an expanding nut or nuts, or some other suitable means.

To enable a hole which is to receive an anchor to be cut or drilled in the rock with facility, a tool-guide is required, and this may be a small tube or pipe, like the drill-pipe 14 (Fig. 2), inserted in the pile-tube and resting on the bearing-stratum. By operating a drill in this drill-pipe, or guide-pipe, the drill having a working fit therein, the hole can be readily cut in the rock at the desired place, and then the guide-pipe may

be further utilized to insure the insertion in the drilled hole of the anchor, passed through and guided by the pipe.

Sometimes it will be desirable, and perhaps it will be necessary, to fill the pile-tube immediately after it has been driven to the bearing-stratum, especially where there is quicksand and ground-flows are apt to occur during the drilling. Then as soon as the interior of the pile-tube has been cleared, if it contains material that ought to be removed, a drill-pipe may be inserted in the pile-tube which may then be filled with concrete, and thereafter the drilling and setting of the anchor rod or post can be done at the pleasure of the workman.

In Fig. 2 a drill-pipe 14 is shown embedded in the filling 15 of a pile and extending from the pile-tube 16 to the bearing-stratum 17, the pile being anchored by means of the post 18 fitting in the drill-pipe and the rock. Obviously a pile may be anchored by means of two or more posts or rods. The large pile which is shown in Fig. 4 contains four drill-pipes 14 in which are four anchor-posts 18 that extend into holes cut in the bearing-rock by a drill operated in and through the drill-pipes, this large pile comprising the pile-tube 19 and the filling 20 in which the drill-pipes are embedded.

The manner of carrying out the method is illustrated in Figs. 5 to 9, wherein the successive steps are shown. In Fig. 5 is disclosed the first step which consists in sinking the tubular casing 16 and guide tube 14 to the bearing stratum 17. Fig. 6 discloses the drilling operation wherein a drill 21 and driving means 22 are conventionally disclosed. Fig. 7 shows the casing and tube after the space between the two has been cleared of earth. Fig. 8 shows the parts after the post 18 has been positioned, and Fig. 9 shows the completed and concrete-filled pile.

In steel pile-foundations formed as herein described some piles are required to sustain loads of more than a hundred tons each. The danger of serious damage being done to the great buildings and other heavy structures which they support, if the piles slip at the base so as to allow the structures to settle, has long been known and in some cases such damage has occurred, but by means of this invention it can now be easily prevented.

Having thus described my invention, what I claim as new and desire to secure by Letters Patent, is:

The process of anchoring tubular piles which consists in sinking a tube through the super-stratum to the bearing stratum, inserting a guide tube longitudinally through the tube to the bearing stratum, inserting a boring tool through the guide tube, the ex-

ternal diameter of the boring tool being the same as the internal diameter of the guide tube, drilling a hole in the bearing stratum with the boring tool, evacuating the space

5 between the guide tube and the wall of the first tube and evacuating the guide tube, filling the guide tube with an anchoring post fitting in and extending from the top of the

guide tube to the bottom of the hole, and filling the space between the guide tube and inner wall of the first tube with cementitious material.

JOHN BYRON GOLDSBOROUGH.
